UNITED STATES PATENT OFFICE.

JAMES CLAY SIMMS AND GEORGE H. HUSTON, OF CINCINNATI, OHIO;
SAID SIMMS ASSIGNOR TO SAID HUSTON.

GAS-BURNER.

SPECIFICATION forming part of Letters Patent No. 761,924, dated June 7, 1904.

Application filed January 31, 1903; Serial No. 141,376. (No model.)

To all whom it may concern:

Be it known that we, JAMES CLAY SIMMS and GEORGE H. HUSTON, of Cincinnati, in the county of Hamilton and State of Ohio, (whose 5 post-office address is Cincinnati, Ohio,) have invented a certain new and useful Improvement in Gas-Burners, of which the following is a specification.

Our invention consists of a gas-burner with a combination needle-valve and knurled thumb-screw so adjusted as to extend through crimped tubing and regulate the needle-valve, which regulates the flow of gas to a high or low pressure by allowing the thumb-screw to screw 15 upward and downward to edge of crimp in tubing.

The invention has for its object to provide crimped tubing which when crimped in the upper crimp will prevent the thumb-screw 20 from screwing off the needle-valve entirely and the lower crimp preventing the needle-valve from closing up entirely and allowing small flow of gas to keep burner continuously 25 burning, thereby acting as a by-pass until the gas is entirely shut off.

Figure 1 is a view in elevation of the burner. Fig. 2 is a vertical sectional view thereof. Fig. 3 is a perspective view of the valve.

The burner comprises in its construction a tube A, having air-inlet openings D for the purpose of admitting air to be mixed with the gas. The tube is also provided with openings at each side, the walls of said openings being crimped or turned in, as shown at E, to form 30 stops for the gas-regulating device to be hereinafter referred to. A gas-supply member C is internally threaded to be attached to a gas-fixture, and this gas-supply member has a nipple c', which is externally threaded to 35 receive the thimble b. The thimble is provided with a flange B, which is moved in the

opening bounded by the crimped portions E, so that as said flange B is moved up or down a predetermined distance contact is made with the said crimped portions to arrest the movement of the said flange and its thimble. The upper end of the nipple terminates in a needle-valve c'', which coacts with a valve-seat b' of the thimble, thereby affording means for regulating the flow of the gas therethrough. It 45 is our purpose to have the relation of the flange B and the crimped portion E such that the valve-seat b' cannot be seated on the valve c'', but there remains always a small discharge-opening which will support a flame, so that 50 in turning on the light a match need not be used, as there will always be a small flame at the discharge end of the thimble.

We claim—

1. In a gas-burner, a tube having openings 60 with the edges thereof turned in to form shoulders, a gas-supply member in the end of the tube having a nipple with a needle-valve on its end, a thimble threaded on the nipple and having an opening controlled by the needle-valve, and a flange on the thimble having its periphery projecting through the openings of the tube, substantially as described.

2. In a gas-burner, a tube having openings with inturned edges, a needle-valve for controlling the flow into the tube, a thimble co-acting with the valve, having a flange projecting through the openings of the tube and limited in its movement by the inturned edges of the tube. 75

In witness whereof we have affixed our signatures in the presence of two witnesses.

J. CLAY SIMMS.
GEORGE H. HUSTON.
